DESIGN FOR A STOPPER TOP

Michael Piluso, Brooklyn, N. Y.

Application November 2, 1938, Serial No. 80,833

Term of patent 7 years

To all whom it may concern:

Be it known that I, Michael Piluso, a citizen of the United States, residing in the Borough of Brooklyn of the city of New York, in the State of New York, have invented a new, original, and ornamental Design for a Stopper Top, of which the following is a specification, reference being had to the accompanying drawing, forming part thereof.

Fig. 1 is a top plan view of a stopper top embodying my new design; and

Fig. 2 is a side elevation of the same.

I claim:

The ornamental design for a stopper top, as shown.

MICHAEL PILUSO.
